US00D644731S

(12) **United States Design Patent**
Fangrow, Jr.

(10) **Patent No.:** **US D644,731 S**
(45) **Date of Patent:** **** Sep. 6, 2011**

(54) **MEDICAL CONNECTOR**

(75) Inventor: **Thomas F. Fangrow, Jr.**, Mission Viejo, CA (US)

(73) Assignee: **ICU Medical, Inc.**, San Clemente, CA (US)

(**) Term: **14 Years**

(21) Appl. No.: **29/376,647**

(22) Filed: **Oct. 8, 2010**

Related U.S. Application Data

(63) Continuation of application No. 12/730,074, filed on Mar. 23, 2010.

(51) **LOC (9) Cl.** **24-02**

(52) **U.S. Cl.** **D24/129**

(58) **Field of Classification Search** D24/127-129; 604/905, 533, 535, 167.03, 167.04, 247-248, 604/167.06, 249, 403, 256, 5

See application file for complete search history.

CLAIM

The ornamental design for a medical connector, as shown and described.

DESCRIPTION

FIG. 1 is a top perspective view of a medical connector embodying my new design.

FIG. 2 is a bottom perspective view of the medical connector of FIG. 1.

FIG. 3 is a right side view of the medical connector of FIG. 1, the left side view being a mirror image thereof.

FIG. 4 is a top plan view of the medical connector of FIG. 1; and,

FIG. 5 is a bottom plan view of the medical connector of FIG. 1.

The broken lines shown in the Figures are included for the purpose of illustrating portions of the article and form no part of the claimed design.

1 Claim, 3 Drawing Sheets
